UNITED STATES PATENT OFFICE.

CHARLES VOLNEY KERR, OF WELLSVILLE, NEW YORK.

EXHAUST FOR STEAM-TURBINES.

1,131,645.

Specification of Letters Patent. Patented Mar. 9, 1915.

Application filed February 7, 1914. Serial No. 817,825.

To all whom it may concern:

Be it known that I, CHARLES V. KERR, a citizen of the United States, residing at Wellsville, in the county of Allegany and State of New York, have invented certain new and useful Improvements in Exhausts for Steam-Turbines, of which the following is a specification.

My invention relates to improvements in exhaust passages for steam turbines.

The objects of my invention are: First: to utilize the residual velocity of the exhaust steam, as it leaves the buckets or vanes of the final stage of expansion, to reduce the back pressure of the turbine. Second: to so arrange and construct the exhaust passage of a turbine, that the residual velocity remaining in the exhaust steam after leaving the last bucket or vane can be utilized to increase the exhaust pressure, instead of wasting it in needless and obstructing eddies, and thereby effect a lower pressure in the exhaust end of the turbine casing than in the connected exhaust pipe or chamber, heretofore used. Third: to so construct and arrange the exhaust passage of the turbine, that the residual velocity remaining in the exhaust steam is utilized uniformly around and at all the buckets of the last bucket wheel or rotor, thereby providing a uniform pressure and discharge of fluid pressure at the periphery of the last bucket wheel, and at the different stages of expansion throughout the turbine. Fourth: other objects and advantages of the invention will appear from the detailed description which will be hereinafter more fully given.

The invention consists of structural features and relative arrangements of the elements of the invention, which will be hereinafter more fully described and particularly pointed out in the appended claims.

In the drawings, in which similar reference characters indicate the same parts in the several figures of drawing; Figure 1 is a longitudinal section on line I—I of Fig. 2, of the exhaust end of a turbine with the improved volute exhaust passage attached thereto; and Fig. 2 is a transverse section on line II—II of Fig. 1.

Referring to Fig. 1 of the drawings, in which the exhaust end of a turbine is represented, 1 is a rotary shaft to which is secured in any suitable manner two rotary wheels 2, and 3, having buckets 2', and 3',

respectively, on their peripheries. 4 is a section of the turbine casing provided with the stationary nozzles 5, for guiding the steam into the buckets 2', and 6 is a ring having stationary reversing nozzles 7, to receive the steam from the buckets 2' on the rotary wheel 2, and guide the same into the buckets 3' on the rotary wheel 3. Said sections or rings 4, and 6, are preferably independent of each other and are dovetailed at their joints, and form no essential part of the present invention, as any other form or type of turbine may be used, but are illustrated in the present instance for the purpose of showing the construction and relation of the improved exhaust passages with a turbine.

The exhaust end of the steam turbine is closed by a head 8, provided with the improved exhaust passage preferably cast therein, said exhaust passage being provided with an exhaust nozzle 9 having its smaller annular opening at the inner side of the head 8 adjacent to and in communication with the final exhaust from the turbine buckets, or exhaust ends of the series of buckets 3', 3', on the last rotary wheel or rotor 3, as shown in Fig. 1. The annular exhaust nozzle 9 expands outwardly and opens into an exhaust passage 10, of increasing cross-sectional area and of volute shape, said passage 10 having an outlet or discharge 11 which is connected to the usual exhaust pipe leading to the atmosphere or condenser, as desired. The bottom of the volute shaped exhaust passage 10 is provided with an opening 12 having a valve, not shown, to drain any water of condensation, or oil, which may collect at this point.

The head 8 is provided with an opening 13 centrally disposed with respect to the volute shaped exhaust passage 10 and annular nozzle 9, for the passage of the shaft 1. A cap 14 carrying the usual stuffing box 15 with packing glands, and a bearing 16, as shown, is firmly secured over the opening 13, and needs no further disclosure, as it forms no essential feature of the present invention.

The operation of the invention is as follows: The steam having been admitted into the inlet of the turbine, it passes through one or more stages, and finally reaches the last stage, and then passes with a residual velocity from the exhaust side of the last series of buckets or vanes 3', 3', on the wheel 110

or rotor 3, into the entire outer or smaller opening of the adjacent annular nozzle 9. The residual velocity remaining in the exhaust steam, and the backward direction of 5 its flow imparted to it by the rotating wheel 3, causes said exhaust steam to pass into the volute exhaust passages 10 in the proper direction and whirl without the various streams issuing from the different buckets 10 3', 3', impinging against each other or against the walls of the volute exhaust passage 10, to form interfering eddies or needless friction against the walls of the exhaust passage.

15 The residual velocity in the annular nozzle 9, and the whirling action within the volute exhaust passage 10 results in a decrease of velocity and an increase of density in the steam issuing from the buckets 3', 3', and an 20 increase in pressure of the exhaust steam. This means, for example, if the turbine exhausts against atmospheric pressure, the steam may expand in the turbine until the 25 pressure in the last stage is somewhat less than atmospheric pressure. Or, if the exhaust is into a vacuum, the pressure in the last stage may be as low as in the condenser, since the decrease in velocity of exhaust may 30 balance the pressure required to overcome friction in piping between the turbine and condenser.

What I claim is:—

1. A steam turbine comprising a cylinder, 35 a rotatable shaft, bucket wheels rotating with said shaft, a volute exhaust passage

having an outlet and an annular inlet and of gradually increasing cross-sectional area from its inlet to its outlet, and an annular unobstructed nozzle having sections in planes passing through the axis of the shaft 40 in the form of a diverging nozzle, the inlet of said annular nozzle being placed at the discharge side of the buckets on the wheel adjacent to the exhaust and the curvature of the outlet of the annular nozzle merging 45 smoothly into the curvature of the annular inlet of the volute exhaust passage.

2. A steam turbine comprising a cylinder, a rotatable shaft, bucket wheels rotating with said shaft, a volute exhaust passage 50 having an outlet and an annular inlet, and an annular nozzle having sections in planes passing through the axis of the shaft in the form of a diverging nozzle, the inlet of said annular nozzle being placed at the discharge side of the buckets on the wheel adjacent to the exhaust and the outlet of the annular nozzle merging smoothly in the annular inlet of the exhaust passage, and said exhaust passage arranged so that exhaust steam from 55 said buckets of said wheel flows around the exhaust passage and issues from said outlet in a direction backward to the direction of rotation of the said bucket wheel.

In testimony whereof I affix my signature 60 in presence of two witnesses.

CHARLES VOLNEY KERR.
